UNITED STATES PATENT OFFICE.

WILLIAM R. BROUH, OF EAST ORANGE, NEW JERSEY, ASSIGNOR TO WESTERN ELECTRIC COMPANY, INCORPORATED, OF NEW YORK, N. Y., A CORPORATION OF NEW YORK.

VACUUM-TUBE BASE.

Application filed December 2, 1920. Serial No. 427,807.

To all whom it may concern:

Be it known that I, WILLIAM R. BROUH, a citizen of the United States, residing at East Orange, in the county of Essex, State of New Jersey, have invented certain new and useful Improvements in Vacuum-Tube Bases, of which the following is a full, clear, concise, and exact description.

This invention relates to vacuum tubes and more especially to the construction of a base therefor.

In the use of vacuum tubes in high voltage, high frequency circuits, much difficulty has been experienced in insulating the lead wires of the grid and anode electrodes. Attempts have heretofore been made to prevent discharges from and corona effects along these lead wires by surrounding them with bodies of insulating material carried by the bottom of the base. These attempts have failed because with currents of high frequency and at high voltages the heating of the insulating bodies due to dielectric hysteresis is so great as to quickly cause deterioration and deformation of the insulation resulting in a breakdown thereof and allowing discharges from the lead wires.

It is an object of this invention to provide a base for vacuum tubes using high voltages and high frequencies in which the lead wires for the electrodes of the tube are insulated from each other and in which the heating of the dielectric of the base is reduced to such an extent that no injurious effects result.

This object is accomplished by using as a part of the base a thin disc composed of material having a low specific dielectric loss as, for example, phenol fibre or "electrosote" and providing terminals in the disc for the electrodes of the tube, said terminals being so proportioned and arranged in the disc as to isolate the anode terminal from the rest and to obtain a minimum potential gradient between the terminals themselves and between the terminals and the shell of the base.

This invention will be better understood by having reference to the following specification and the accompanying drawings wherein Figure 1 is a section on line 1—1 of Figure 2 and discloses a base made in accordance with the invention and Figure 2 is a bottom view of said base.

On the neck 10 of the bulb 11 of the vacuum tube is cemented a metallic shell 12, the free end of which is turned-in as at 13

and in which is rolled an inwardly extending flange 14 near the edge 13. Arranged between the in-turned edge 13 and the flange 14 is the thin disc 15 composed of an insulating material having a very low specific dielectric loss. In this disc are provided apertures in which are located the terminal 16 for the anode of the tube, the terminal 17 for the grid and the terminals 18 for the cathode. These terminals comprise cylindrical members having flanges 19 to contact with one side of the disc to position them in their apertures and collars 20 to contact with the opposite side of the disc to clamp said members in place. These terminals are provided with small axial holes which are countersunk at their ends. The lead wires 21 for the anode, 22 for the grid and 23 for the cathode are threaded through the holes in the terminals 16, 17 and 18 respectively and soldered into the outer ends as at 24 and then flushed off. This arrangement avoids the concentration of dielectric stresses around the small diameter of the lead wires and confines the stresses to the periphery of the terminals, thereby avoiding the possibility of breakdown of the insulation from corona or high dielectric stresses at the surface of the lead wires.

The terminals 16 and 17 are so arranged in the disc 15 that the electrical stresses in the disc adjacent the points of nearest approach of the terminals to the shell and adjacent the point of nearest approach of the terminal 16 to the terminal 17 are all approximately equal. The terminals 18 are so located in the base relative to the terminals 16 and 17 that the electrical stresses in the disc 15 adjacent the points of nearest approach of the terminals 16 and 17 to the terminals 18 are equal to each other and to the aforementioned stresses. Furthermore, the diameter of the terminals 16, 17 and 18 is so adjusted that these equal stresses are approximately the smallest possible consistent with the diameter of the disc. The disc is made as thin as possible without unduly reducing mechanical strength.

This effect is accomplished in a 250 watt tube, by making the disc of "electrosote" about $3 \frac{3}{10}$ " in diameter and approximately $5/32$ " thick and making the effective diameter of the terminals approximately $1/2$ ". These terminals are then so arranged that 16 and 17 lie on a diameter of

the disc and are about $1 \frac{1}{16}$ " apart, the terminal 16 being about $7/8$ " and the terminal 17, $5/16$ " from the periphery of the disc. The terminals 18 are approximately 5 $1/16$ " from the terminal 16 and approximately $19/32$ " from 17.

Vacuum tubes equipped with this type of base may be operated for indefinite periods in circuits in which the peak voltages of the 10 anode and grid at complete modulation are approximately 6000 volts and minus 2000 volts respectively with respect to the cathode and the frequency is approximately 1,000,000 cycles per second. The disc 15 is not heated 15 sufficiently to cause deterioration of its insulating property because the arrangement of the terminals is such as to reduce to a minimum the dielectric stresses in the disc adjacent the points of nearest approach of 20 the high tension terminals to the low potential terminals and because the large surface of the disc for the volume thereof allows a considerable heat dissipation therefrom.

While it is preferable to utilize the described arrangement of the terminals in combination with a thin insulating disc, it is to be understood that they may be arranged as described irrespective of the particular means used for supporting them in the base. 30

What is claimed is:

1. A base for a vacuum tube having electrodes, said base comprising a sheet metal shell, a disc mounted therein, said disc being of insulating material having a low specific dielectric loss, terminals for the electrodes of the tube mounted in said disc, each of said terminals being arranged at one vertex of congruent scalene triangles to establish for the operating voltages of the grid and anode 35 an approximate minimum potential gradient between the terminals for the grid and cathode, between said terminals and the shell, and between said terminals and the terminals of the cathode.

45 2. A base for a vacuum tube having electrodes, said base comprising a sheet metal shell, a thin disc mounted therein, said disc being composed of insulating material having low specific dielectric loss, terminals for the electrodes of the tube mounted in said base, said terminals being arranged at the vertices of congruent scalene triangles the electrical stresses in the disc adjacent the points of nearest approach of the anode 50 terminal to the grid terminal, the cathode terminals and the shell, and the electrical stresses in the disc adjacent the points of nearest approach of the grid terminal to the cathode terminals and the shell established 55 therein at the operating voltages of said grid and anode are reduced to a minimum.

60 3. A base for a vacuum tube having electrodes, said base comprising a sheet metal shell, a thin disc mounted therein, said disc being composed of insulating material hav-

ing a low specific dielectric loss, terminals mounted in said base for the electrodes of said tube, the anode and grid terminals being arranged on a diameter of the disc, the distance between said grid and anode terminals being approximately $1/3$ the diameter of the disc, and the distance between the shell and the anode terminal being approximately $2/5$ of said diameter, the cathode terminals being arranged in the same half-disc with the grid terminal at points equally distant from said grid terminal and also equally distant from said anode terminal. 70 75

4. A base for a vacuum tube having electrodes, said base comprising a sheet metal shell, a thin disc mounted therein, said disc being composed of insulating material having a low specific dielectric loss, terminals for the electrodes of the tube mounted on said base, the anode terminal being spaced from each of the other terminals a distance at least equal to $1/3$ the diameter of the base and from the shell a distance approximately 2/5 of said diameter. 80

5. A base for a vacuum tube having electrodes, said base including a sheet metal shell, a thin disc mounted therein, said disc being composed of insulating material having a low specific dielectric loss, terminals for the electrodes of the tube mounted in said base, said terminals being arranged in the disc with the anode terminal in a different half-disc from the grid and cathode terminals, said cathode terminals being equally spaced from said grid terminal and also being equally spaced 90 95 from said anode terminal. 100

6. A base for a vacuum tube having electrodes, said base comprising a sheet metal shell, a thin disc mounted therein, said disc being composed of insulating material having a low specific dielectric loss, terminals for the electrodes of the tube mounted in said base, said terminals being arranged in the disc with the cathode and grid terminals grouped in one half of the disc and said anode terminal in the other half, said grid and anode terminals being on a diameter of the disc and said cathode terminals being equally spaced from said grid terminal and also from said anode terminal. 110 115

7. A base for a vacuum tube having electrodes, said base comprising a sheet metal shell, a thin disc mounted therein, said disc being composed of insulating material having a low specific dielectric loss, terminals for the electrodes of the tube mounted in said base, said terminals being arranged in the disc with the grid and anode terminals on a diameter of the disc at different sides of and at different distances from the center of the disc and the cathode terminals being located on a chord of the disc at right angles to said diameter and lying between the center of the disc and said grid terminal, said cathode terminals being equally spaced 120 125 130

- from the intersection of said chord and diameter.
8. A base for a vacuum tube having electrodes, said base comprising a sheet metal shell, a thin disc mounted therein, said disc being composed of insulating material having a low specific dielectric loss, terminals for the electrodes of the tube mounted in said base, said terminals being symmetrical with respect to one diameter only, whereby the anode terminal is isolated from the others to establish at operating voltages a minimum potential gradient between the anode and the other terminals and between the anode and the shell.
9. A base for a vacuum tube having electrodes, said base comprising a sheet metal shell, a thin disc mounted therein, said disc being composed of insulating material having a low specific dielectric loss, terminals for the electrodes of the tube mounted in said base, each of said terminals being arranged in the disc at an apex of a scalene triangle, the anode terminal being isolated from the others whereby at operating voltages the electrical stresses in the disc adjacent the points of nearest approach of the anode electrode to the shell and to the other terminals are equal.
10. A base for a vacuum tube having electrodes, said base comprising a sheet metal shell, a thin disc mounted therein said disc being composed of insulating material having a low specific dielectric loss, terminals for the electrodes of the tube mounted in said base, said terminals being arranged in the disc at the corners of a quadrilateral symmetrical with respect to one of its diagonals, said diagonal being coincident with the diameter of the disc, two of said terminals being at different distances from said shell.
11. A vacuum tube base comprising a shell, a disc of insulating material therein, and terminals carried by said disc, the diameter of said disc being not less than twenty times the thickness of the disc.
12. A vacuum tube base comprising a shell, a disc of "electrosote" mounted therein, and terminals carried by said disc, the diameter of said disc being approximately twenty times the thickness of said disc.
13. A base for a vacuum tube having electrodes, said base comprising a cup shaped member, terminals for the electrodes of the tube mounted in said member, each of said terminals being arranged at an apex of one of two scalene triangles having a common leg, to establish at the operating voltages an approximate minimum potential gradient between the terminals for the grid and anode, between said terminals and the wall of said member and between said terminals and the terminals of the cathode.
14. A base for a vacuum tube having an anode, a cathode and a grid electrode, said base comprising a cup shaped member, terminals for the electrodes of the tube mounted in said member, each of said terminals being arranged at the vertices of congruent scalene triangles whereby the electrical stresses in the member adjacent the point of nearest approach of the anode terminal to the grid terminal, the cathode terminals and the wall of said member and the electrical stresses in the base adjacent the points of nearest approach of the grid terminal to the cathode terminals and said wall established therein at the operating voltages of said vacuum tube are reduced to an approximate minimum.
15. A base for a vacuum tube having an anode, a cathode and a grid electrode, said base comprising a member having a circular bottom, terminals for the electrodes of the tube mounted in said bottom, the anode terminal being spaced from each of the other terminals a distance at least equal to $1/3$ of the diameter of the base and from the wall of the base a distance approximately $2/5$ of the diameter.
16. A base for a vacuum tube containing a cathode, an anode and a control electrode, said base comprising a metallic shell, terminals for said electrodes associated with said shell, the terminals for said cathode and control electrodes being spaced apart a distance substantially the same as the distance from the terminal of said anode to said shell, said cathode terminals being at a less distance from said shell than said control electrode terminal.
17. A base for a vacuum tube containing a cathode, an anode and a control electrode, said base comprising a metallic shell, terminals for said electrodes associated with said shell, the terminals for said cathode and control electrodes being spaced apart a distance substantially the same as the distance from the terminal of said anode to said shell, said last mentioned terminal being approximately twice as far from said shell as said other terminals.
18. A base for a vacuum tube having an anode, a cathode and a grid electrode, said base comprising a member having a circular bottom, terminals for the electrodes of the tube mounted in said bottom, the anode terminal being spaced from each of the other terminals a distance at least equal to $1/3$ of the diameter of the base and from the wall of the base a distance approximately $2/5$ of the diameter, said other terminals being spaced apart a distance approximately $2/5$ of the diameter.
19. A base for a vacuum tube containing a cathode, an anode and a control electrode, said base comprising a shell, terminals for said electrodes associated with said shell, said cathode terminals being symmetrically

arranged with respect to the anode and control electrode terminals, each of the cathode terminals being spaced from the control electrode terminal a distance approximately 5 equal to the distance between the anode terminal and the shell, and said anode terminal being spaced from the shell a greater distance than is any of the remaining terminals.

20. A base for a vacuum tube containing 10 a cathode, an anode and a grid electrode, said base comprising a shell, terminals for said electrodes associated with said shell, said cathode terminals being symmetrically arranged with respect to the anode and grid 15 terminals, said grid terminal being at a greater distance from said anode terminal than are the cathode terminals, each of said cathode terminals being spaced from the grid terminal a distance less than the distance between the anode terminal and the shell, said anode terminal being spaced from the shell a greater distance than is said grid terminal and said grid terminal being spaced 20 a greater distance from said shell than are said cathode terminals.

21. A base for a vacuum tube having electrodes comprising a member having a circular bottom, terminals for the electrodes of the tube mounted in said bottom, one of said terminals being spaced from each of the other terminals a distance at least equal to 1/3 of the diameter of the base and from the wall of the base a distance approximately 2/5 of the diameter. 30

22. A base for a vacuum tube having electrodes comprising a member having a circular bottom, terminals for the electrodes of the tube mounted in said bottom, one of said terminals being spaced from each of the other terminals a distance equal to 1/3 of the diameter of the base and from the wall of the base a distance approximately 2/5 of the diameter, said other terminals being spaced apart a distance approximately 2/5 of the diameter. 35

In witness whereof, I hereunto subscribe my name this 23rd day of November A. D., 1920.

WILLIAM R. BROUGH.
